UNITED STATES PATENT OFFICE.

HARRIE A. BALLARD, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

CHAIN-STITCH SHOE-SEWING MACHINE.

1,110,863.

Specification of Letters Patent.

Patented Sept. 15, 1914.

Application filed December 19, 1907. Serial No. 407,143.

To all whom it may concern:

Be it known that I, HARRIE A. BALLARD, of Boston, in the county of Suffolk and State of Massachusetts, have invented certain new 5 and useful Improvements in Chain-Stitch Shoe-Sewing Machines, of which the following is a specification.

This invention has relation to shoe sewing machines which employ waxed thread, and 10 more particularly to such of said machines as make a chain stitch, although certain features of the invention may be incorporated in those which make a lock stitch.

The principal object of the invention is 15 to produce a machine of the general class referred to, which may be run at high speed, and which at the same time will make an accurate and tight seam.

Another object of the invention is to avoid 20 a complication of parts and make the mechanism simple in construction, and well balanced and efficient in operation. Heretofore it has been the practice in commercial machines to employ an awl in connection with 25 the needle, but I have dispensed with this element and cause the needle to make its own aperture in the work and to feed the work. In order, however, that the needle may not be strained by the side thrust in feeding the 30 work, I employ a member or instrumentality which coöperates with the needle in its feeding movement. This instrumentality or member may likewise serve the purpose of a channel guide or opener. The needle and its 35 coöperating feeding member are both mounted, as a matter of convenience, upon the same slide or movable support, and are moved simultaneously to effect the feeding of the work. Mechanism is utilized to move 40 the coöperating feeding member or instrumentality forward and backward so as to engage the work and then to release it, the member thus having what is called "a four-motion" movement. The said member or 45 instrumentality also holds the work against the thrust of the needle when the latter is moved through its penetrating stroke, and in order to resist the thrust upon the work when the needle is withdrawn therefrom 50 and is drawing back the loop, I employ a combined welt guide and work gage, which bears against the work at two distinct or separate points on both sides of the needle, and between which the needle reciprocates

laterally. This part, to wit, the combined 55 welt guide and work gage, serves to hold the work from receding when the needle and its coöperating feeding member are returning after having fed the work. Regarding the welt guide and the work gage as separate 60 entities, they are mounted upon the same movable support, said support being positioned automatically in accordance with the thickness of the parts of the shoe being sewed, and then locked. By automatic 65 mechanism, the support is released and moved away from the work when the work is being fed, and is then forced forward and locked while the needle is being returned to its starting point and forced through the 70 work. The said support for the welt guide is so mounted that, notwithstanding its movement, it keeps a predetermined stitch-receiving line of the welt in the path of the 75 needle. The welt in passing through the guide is creased, and it is desirable that the needle should pass through the crease. Hence, since the needle moves through an arc, the support is mounted so that it too moves through a substantially similar arc, 80 and thus when the welt guide moves away from the work, the crease in the welt follows the path of the needle, in consequence of which the needle always penetrates the 85 crease irrespective of the thickness of, or the number of layers of leather and canvas in the work. The combined welt guide and work gage, practically render unnecessary the usual work support which is common to 90 such machines, although one may be employed if the operator desires. The work gage bears against the upturned portion of the sewed welt whereas the end of the welt guide bears against the upturned edge of the upper and wale or flange of the inner 95 sole, so that with the frictional engagement of the walls of the welt guide with the welt, the resistance of the welt, and the engagement of said guide and gage with the work, the work is effectively prevented from receding when the needle is returning after having fed the work.

To furnish additional strength to the needle for effectively feeding the work, I employ a needle guard, and novel mechanism for operating it. When the needle is moved to penetrate the work, the guard is moved forward at a higher speed into

close proximity to the work, where it remains while the needle penetrates the work and receives the loop of thread. The needle carrier is, in the present case, in the form of a toothed segment, which is engaged and operated by a toothed segmental lever. The guard, however, is mounted on a carrier (movable about the axis of the needle carrier) and it is connected by a link with the 10 said segmental lever. This link and the lever form, as it were, a toggle which, when straightened, causes an initial rapid movement of the guard carrier which movement ceases before the needle completes its penetrating stroke. The thread tension devices are provided with means by which the tension is released when the power shaft is moved reversely, as when the needle is being positioned to permit the insertion or removal of a shoe into or out of position. In connection with this tension-releasing mechanism, I also employ means by which the welt guide and work gage are released and moved away from the work upon a reversal 25 of rotation of the power shaft.

On the accompanying drawings which illustrate one embodiment of the invention, Figure 1 represents in front elevation a chain-stitch shoe sewing machine. Fig. 2 30 represents a side elevation thereof. Figs. 3 and 4 illustrate the operation of the thread finger and the looper. Figs. 5 and 6 illustrate the means for adjusting the looper fulcrum. Fig. 7 illustrates the needle and its 35 carrier, the needle guard and its carrier, the welt guide, and the channel guide, and the relation of the said parts. Figs. 8 and 9 illustrate the combined welt guide and work gage, Fig. 9 showing the gage against the 40 upturned portion of the sewed welt. Fig. 10 is a rear elevation of the machine, illustrating in section the tension-releasing devices. Fig. 11 illustrates the mechanism for locking, releasing and moving the welt guide 45 and work gage, the work rest, and operating the tension-releasing devices. Fig. 12 represents a horizontal section through a portion of the machine and illustrates the work rest, the combined work gage and welt guide, the 50 mechanism for controlling them and the looper. Fig. 13 represents in front elevation the needle carrier and its support, and the needle guard. Fig. 14 represents a side elevation thereof. Fig. 15 represents a section on the line 14-14 of Fig. 14. Figs. 16 and 17 respectively illustrate the needle carrier, and the needle-guard carrier. Figs. 18 and 19 show the gearing for operating the looper. Figs. 20 and 21 represent developments of the two gears. Fig. 22 represents the needle guard and the needle in a different relative position than that shown in Fig. 14.

It should be understood that the illustrated machine is not the only embodiment

of which the invention is capable, that the various details of construction may be varied without departing from the spirit and scope of the invention, and that the phraseology herein adopted is for the purpose of 70 description and not of limitation.

On the drawings, the head of the machine is illustrated as having a base 30 adapted to be supported upon a suitable column or upright. From this base rises a 75 solid upright portion or neck 31 which supports a hollow cylindrical casing 32. The upper portion of this casing, which is shown in section in Fig. 1, is indicated at 33 and is hinged to the lower portion as at 34 so as to be capable of being moved to an upright position. The casing forms an inclosing covering for those parts of the machine which are mounted upon the power shaft. The chamber within the inclosing casing is 80 divided from front to rear by a vertical partition formed by webs 35, 36 so as to provide two separate compartments 37 and 38 for a purpose to be described. Extending transversely through the chambers 37, 38 85 is a power shaft 39 which is equipped with the usual driving pulleys, not shown, and also with a hand wheel, not shown, by which it may be rotated manually when desired.

In the front of the machine, there is a 90 laterally movable slide 40 movable between guides or gibs 41, 42. This slide serves to support the needle carrier, and is reciprocated to effect the feeding of the work when the needle is engaged with the latter. The 100 reciprocation of the slide is effected by a cam disk 43, secured upon the power shaft 39 within the chamber 37 of the head, and a lever 44 carrying on its free end a roll 45 extending into a peripheral cam groove 46 105 in said disk.

The lower end of the lever 44 is fulcrumed upon a stud 47 attached to the front of the head, and the said lever is provided with a longitudinally adjustable stud 48 extending 110 through a slot 49 in the slide, as clearly shown in Fig. 1. By adjusting the said stud 48, the feed of the work may be varied as to length. The slide 40 has a bracket 50 which extends downwardly and rearwardly 115 as shown in Fig. 7. This bracket, as shown in Figs. 13 and 15, is recessed to receive the needle and needle-guard carriers. The recess is closed on one side by a plate 51 secured to the bracket by suitable attaching devices as indicated at 52, 53, Fig. 14. A stud 54 is supported in the plate 51 and the bracket 50, and serves as a fulcrum or pivot about which the needle carrier and the needle-guard carrier may be oscillated, said 120 parts being located in the recess in the bracket.

The needle carrier is indicated as a whole at 55, the needle 56 being secured thereto by a clamp 57 and screw 58. The needle car- 130

rier has a hub and a toothed segment, the latter being engaged by a complementary toothed segment 59 upon a lever 60 (see Fig. 7) which lever is fulcrumed upon a stud 61 attached to the front portion of the head. The oscillation of the lever 60 effects the oscillation of the needle carrier. The needle guard is indicated at 62. It has an aperture 63 through which the needle passes as shown in Figs. 13 and 14. The guard is formed on a carrier 64 fulcrumed upon the stud or pivot 54. The carrier is sector-shaped and is recessed on one side so as to receive between it and the bracket 50, a link 65 pivotally connected to the stud 66 projecting laterally from the carrier.

The link 65 has an elongated laterally projecting stud or pindle 67 which projects through an aperture 68 in the lever 60. The lever 60 and the link 65 constitute, as it were, a toggle which is straightened when the lever 60 is oscillated rearwardly from the position shown in Fig. 7. Since the slide which supports the needle and the needle-guard carriers is reciprocated laterally to feed the work, the pin 67 has a sliding engagement with the lever 60, and the teeth of the segment 59 are wide enough so as to maintain a constantly intermeshed relation with the teeth of the needle carrier as the latter is moved axially.

Assuming that the parts are in the relation shown in Fig. 7, it will be seen that, as the lever 60 is moved to the right, the toggle comprising the lever 60 and the link 65 will be straightened rapidly so that the needle guard will be moved simultaneously with the movement of the needle carrier. The speed of the needle-guard carrier will be greater than that of the needle carrier, but its speed will decrease as the toggle approaches its straightened position in Fig. 22. When the axes of the studs 61, 67 and 66 are in line, the forward movement of the needle guard will cease, and as the lever 60 continues to move to the right, the needle will be advanced to its extreme of movement, the needle guard retarding to some extent. The forward movement of the needle guard is sufficient to bring it in close proximity to the work, this occurring before the needle is moved laterally to feed the work, and during such feeding movement, the needle guard will remain close to the work so as to resist the lateral strain on the needle. The needle guard carrier and the needle carrier are thus actuated by the same lever simultaneously but at different speeds and through different arcs of movement.

The lever 60 may be oscillated by any suitable means, although I prefer to employ an eccentric, since it occasions less vibration than other forms of power-transmitting devices. On the shaft 39 and in the compartment 37 is placed an eccentric 70. The eccentric

strap 71 is connected to a rod 72, having on its end a stud 73 which is adjustable in a slot 74 in the lever 60, said slot being substantially radial of the stud 61.

In order that the needle may have assistance in feeding the work, and also in order that the thrust of the needle against the work may be resisted, I provide a member or instrumentality which conveniently serves both purposes. This member may also conveniently serve as a channel guide or opener, and I shall refer to it by that name. It consists of a finger 75, see Figs. 1, 2 and 7, the lower end of which is curved and pointed so as to extend into the channel in the inner sole and bear upon said inner sole. The shank of the finger is secured upon the end of one arm of a two armed lever 76 which is fulcrumed substantially midway between its ends upon a stud 77 projecting laterally or to the right from the end of the slide 40. The end of the other arm of said lever is equipped with an elongated pin 77 upon which is slidably mounted a roll 78. Said roll has at its end, flanges which straddle a cam 79 formed on the end of the hub of the lever 60, see Fig. 1. The said cam has a depression which is so located that, when the needle has been withdrawn to its limit of movement, the roll 78 will lie in said recess under tension of a suitable spring to move the channel guide to the position shown in Fig. 7. As soon, however, as the needle begins its forward movement, the roll 78 rides up out of the recess and the channel guide is moved into engagement with the upstanding channel flap as indicated in dotted lines.

Upon examination of Figs. 1 and 8, it will be seen that the channel guide is out of alignment with the needle, so that, when the needle has penetrated the work, it will engage the side edge of the finger or channel guide and hence, when the needle is fed laterally, the finger or channel guide will be fed simultaneously with it so that the point of the needle will be relieved from any lateral strain. Thus this member 75 cooperates with the needle in feeding the work. Its end is also in engagement with the work for this same purpose, and it operates in the nature of a clamp to engage and feed the work. Its movement is inward, or to the right in Fig. 7, to engage the work and hold it against the thrust of the needle, then axially with the needle to feed the work, then outward or to the left after the needle has been withdrawn from the work, and then axially back to its original position or starting point as indicated by the dotted lines in Fig. 7.

The looper mechanism is substantially similar to that set forth in my co-pending application Serial No. 408,034 filed December 26, 1907, now Patent No. 1,075,082, dated 130

Oct. 7, 1913. It consists of a looper whose delivery point is caused to encircle the needle in such wise as to cross the bights of the loop so that, when the needle recedes through the work, the loop forms what is termed a "blackwall hitch". The looper is indicated at 80 and it has a tubular nose or delivery nozzle 81. The upper end of the looper is clamped in the bent end of a sliding bar 82 as best shown in Fig. 12. This bar is arranged to slide in guides 83, 83 in the ends of a yoke 84. Midway between its ends, the yoke is fitted friction tight upon an upright stud or fulcrum 85. The said stud is supported in a hub 86 formed on the end of the block 87 attached to an extension projecting laterally from the neck 81 as shown in Figs. 1, 5 and 12. Between the stud 85 and the hub 86, there is an eccentric sleeve or bushing 88, the lower end of which is hexagonal, as indicated at 89, so that it may be rotated for the purpose of adjusting the stud to effect an adjustment of the yoke 84 and thus increase or decrease the radius of the arc of movement of the looper and also to adjust the looper laterally.

A set screw 90 is passed through the hub 86 so as to secure the eccentric sleeve after adjustment. A collar 91 encircles the sleeve and is secured thereto by a screw 92 for a purpose to be later indicated. The rear end of the looper bar 82 is pivoted upon a crank pin 93 projecting downwardly from the disk 94 secured to the lower end of an upright shaft 95. This shaft is journaled in bearings 96, 97, as shown in Fig. 2, and extends upwardly into the chamber or compartment 38 in the hollow head. Upon its upper end, the shaft 95 is equipped with a spiral gear 98 which intermeshes with a driving gear 99 on the power shaft 39. The teeth upon the two gears 98, 99 are so formed that the gear 98, during one rotation of the shaft 39, is caused to rotate through an arc of more than 360° (substantially 450°) at which time it comes to a state of rest and is then reversely rotated through an arc equal to the difference between 360° and its first movement (to wit 90°) to bring it to its original starting point where it remains once more in a state of rest.

The development of the gear 99, as illustrated in Fig. 21, shows that the gear has a long series of teeth *a* of one pitch and a short series of teeth *b* of another pitch. These are connected by longitudinal ribs *c c'*. The gear 98 has one long series of teeth *d* and a short series of teeth *d'* which are so formed that they may be engaged by either the teeth *a* or the teeth *b* of the gear 99. At the ends of the series *d'* are grooves *e e'* which may be engaged by the ribs *c c'* respectively.

As the shaft 95 is rotated, the yoke 84 will be rocked and the bar 82 will be reciprocated

and rocked to cause the looper to traverse the path indicated by dotted lines in Fig. 4. It will be observed from Fig. 1 that the looper-driving gearing is located in a separate compartment 38. This is to enable me to place a bath of oil in the compartment so that the gear 99 will dip thereinto to effect its thorough lubrication. In this last-mentioned figure, the needle has fed the work and has moved into position to receive the loop of thread which is to be laid upon it by the looper.

For the purpose of measuring out the thread so that it will not reeve through the barb of the needle, I employ a thread finger which is indicated at 100. It has at its lower end a lateral hook 101. This finger is formed on or secured to the end of a rock shaft 102. This shaft is journaled in a bearing 103 carried by a bracket 104 which is bolted to the front of the head, as shown in Figs. 1 and 2. Secured upon the shaft is a toothed segment 105, the teeth of which engage complementary teeth on the curved arm 106 of the two armed lever fulcrumed on the stud 61. The other arm 107 of this lever has a roll extending into a cam groove in the face of the cam disk 43. The oscillation of the two armed lever 106, 107 effects a back and forth oscillation of the thread finger 81 so as to cause the hook of the thread finger to engage the thread and draw off a sufficient amount for the stitch, as indicated in Figs. 3 and 4, after which it moves outward to release the thread.

The take-up consists of a bell crank lever having a relatively short arm 108 and a long arm 109, the latter carrying at its forward end a thread truck 110. This lever is also fulcrumed upon the stud 61 and its arm 108 is provided with a roll located in a cam groove in the face of the cam disk 43. An inclined tubular guide 111 extends from the rear of the machine upwardly and forwardly to carry the thread from the tension sheave to the take-up. Between the end of the tube 111 and the truck 110, there is interposed an auxiliary spring take-up consisting of a spring tension lever 112 carrying on its end a thread truck 113. The thread passes from the hub of the said lever under the truck 113, over the truck 110, and thence to the tubular nozzle of the looper. The auxiliary lever 112 is fulcrumed upon a stud projecting laterally from the bracket 104, and the truck 110 abuts against a face 114 on the said bracket. The trucks 113 and 110 are grooved and guards are provided to prevent the thread from leaving them as indicated at 116, 117. The tension sheave, about which the thread passes before it enters the guide 111, is shown at 118, see Figs. 2 and 10. Its hub 119 is journaled upon the hub 120 of a disk 121 secured upon a rod 122 which is supported in a bracket 123 on

the rear of the head. The sheave 118 is recessed to receive the disk and also a friction washer 124. The hub 119 of the sheave projects beyond the end of the hub 120, and against the end of the hub 119 is placed a plate or lever 125 which is held thereagainst by a spring 126 located between it and a flange nut 127 screwed on the end of the rod 122. The lever 125 is provided with a sleeve 10 or hub 128 extending into the hub 119. The two hubs 120, 126 have complementary cam teeth so that, when the lever 125 is rocked, it is forced axially against the tension of the spring so as to release the sheave 118, 15 and permit it to rotate freely relatively to the friction washer 124. When the parts are in the position shown in Fig. 10, however, the spring 126 bearing against the lever 125, forces it and the sheave to the left 20 so as to cause the inner face of the sheave to bear frictionally against the friction washer 124 which in turn bears against the stationary disk 121.

Mechanism is provided by which the lever 125 is rocked so as to release the sheave and permit it to rotate freely. This mechanism consists of a lever 1128. This lever has a bifurcated or yoke-shaped upper end terminating in two hubs 129, 130 which are journaled upon a stud 131 in the bearings 132, 132. This lever 1128 has a pin 133 extending into a slot in the end of the lever 125 as shown in Fig. 11. Projecting from the hub 130 is an arm or lever 134 upon the end of which is pivoted a pawl 135 which is held against the hub 131 of the cam disk 43 by a spring 136. Said hub has a tooth 432 which, when the power shaft is rotated in its normal direction, as indicated by the arrow, for forming the stitch, passes under the pawl 135 without operating the lever. When the power shaft is rotated in the opposite direction, the tooth 432 engages the pawl 135 and rocks the arm 134 rearwardly 45 so as to swing the arm 1128 forwardly and thereby rock the arm 125 to release the tension sheave. The lever formed by the two arms 134, 1128, is also utilized for another purpose which will be presently explained.

Although it is not essential, I have shown the machine as being equipped with the usual work rest 140 (Fig. 12). This is a bar having a curved forward end against which the upper of the shoe may be held by the operator. A similar work rest is shown in U. S. Letters Patent 412,704, October 8, 1889. This bar slides in guides on the left side of the machine and is provided with a rack 141 (Fig. 10) intermeshing with a pinion 142 mounted loosely on a rock shaft 143 (Figs. 2 and 12). The pinion is formed on or connected to a ratchet 144 (Figs. 1, 2, 19 and 12) which is in turn connected to 60 the shaft 143 by a coil spring 145 (Figs. 1, 10 and 12). A pawl 146 (Figs. 10 and 12) is adapted to engage the ratchet 144 to prevent its rotating after the spring 145 has rotated it and the pinion 142 to advance the rest in the usual way. This mechanism is not novel with me, having long been in use on machines for accomplishing the same purpose. The lever 1128 has a finger 150 which may engage a pin 149 on the pawl 146 so as to raise it and free it from 70 the ratchet when the power shaft is reversely rotated.

I have already explained how the forward thrust of the needle against the work is resisted by a member located on the opposite 80 side of the work. When the needle is being withdrawn from the work and the loop or thread is being drawn therethrough, they tend to pull the work toward the head of the machine. Heretofore it has been resisted 85 by the work rest such as I have described. This work rest engages the upper of the shoe at some little distance from the needle, so that the work tends to oscillate about the rest as a fulcrum. It has been necessary for 90 an operator to manually resist this pull as best he may, but it results in a constant vibration or oscillation of the shoe and is detrimental to the formation of an accurate seam. I have provided, for resisting this 95 inward pull upon the work, an instrumentality which bears against the work on the needle side in close proximity to the needle. I have termed this instrumentality a work 100 gage in contradistinction to the usual work rest such as I have shown at 140. In addition thereto, I have so formed and located this rest, that with it may coöperate the welt 105 guide which also bears against the upturned upper and inner sole flange and assists in 110 resisting the inward strain upon the work. The work gage is indicated at 1500 and the welt guide at 151. In front elevation, as indicated in Figs. 1, 8 and 9, the welt guide is inclined inwardly to the left and downwardly. It consists of a block 152 which has a flat face *f* with an end face *g* at very nearly a right angle thereto.

On the flange 153 is secured a spring plate 154, the end of which is curved around and 115 over the edge of the end face *g* so as to form an angular guideway for the welt which is indicated at *x*. The spring plate is secured in position by a screw 155, there being utilized a welt gage 156 consisting of a bent wire 120 or pin as shown in Fig. 8. When the welt is drawn through the welt guide thus formed, it is bent along a longitudinal line to form a longitudinal crease which I have indicated at *x'*. The delivery end of the welt guide 125 projects slightly forward of the end of the work gage 1500, as shown in Fig. 9, so that the end of the work gage may bear against the stitched welt and so that the curved end 130 of the welt guide may bear against the up-

turned edge of the upper and of the flange or wale on the inner sole. In Fig. 9, the edge of the upper is indicated at *y*, the flange or wale at *z*, and the upturned channel flap at *w*. When the needle penetrates the work, it passes close to the delivery end of the welt guide as shown in Fig. 9. The under face of the work gage and the under edge of the welt guide bear against the upper face of the welt and the upper on the edge of the inner sole. The welt guide and the work gage are both formed on the same shank 157, and between them there is an open passageway 158 through which the needle may pass, which passageway is wide enough to accommodate the greatest lateral movement of which the needle is capable in feeding the work. The needle penetrates the work at a point close to the welt guide, and is withdrawn from the work when relatively near the gage 1500. The gage bears against the upturned part of the welt between its inner edge and the line of stitches, and its bearing surface is sufficiently broad to afford an ample abutment to resist the backward pull of the needle. The welt guide also resists the backward pull by reason of its engagement with the upturned margin of the upper. The under surface of the gage bears upon the welt between the outer edge and line of stitches, and is therefore adapted to resist the upward pull of the thread due to the rising of the needle. The two work-engaging surfaces of the gage have distinct though similar functions, but they contribute toward a single result, to wit, holding the work so as to prevent dislocation due to retractive movement of the needle.

40 The delivery point of the welt guide is so close to the stitched upper that it and the work gage tend to hold the shoe against retrograde movement when the needle is moving axially to its initial position after 45 having fed the work.

During the feeding movement of the needle, the work gage and the welt guide are moved backward to release it and are then moved forward so as to again engage the work, being automatically locked in the position in which they are stopped by reason of the thickness of the work. The releasing movement of the welt guide and work gage is in a curved path with a radius substantially the same as the radius of the arc of movement of the needle. The creasing corner of the welt guide at its delivery end is such that the crease in the welt intersects the curved path of the needle. I find it desirable to preserve this intersecting relationship in order that the needle may always penetrate the welt in a predetermined stitch-receiving line, regardless of the exact point at which the welt guide is stopped by the work in its forward movement. The shank

152 is adjustably secured to a bar 159 by means of a screw 160, and a screw 170 passing through a slot in the end of the bar. The bar itself is pivotally supported upon pivot studs 171, 172 in the ends of parallel links 173, 174, see Fig. 2. The link 173 at its upper end is fulcrumed upon a stud 300 projecting from the right side of the neck 31. The link 174 is fast upon the shaft 143 hereinbefore referred to. The radial length of the links 173 and 174 is substantially equal to the radius of the arc of movement of the needle so that, when the bar 159 is moved back and forth, as will be explained, the predetermined stitch-receiving line of the welt continues to intersect the path of the needle without twisting the welt. The bar is held forward yieldingly by a spring 176, the rear end of which is attached to the stud 172 and the forward end to a hook on the collar 91 (see Figs. 1 and 5). It is adapted to be locked in this position by a pawl 177 loosely mounted on the same pin 178 which supports the pawl 146, previously referred to, as shown in Fig. 12. The pawl 177 is caused by a spring 179 to engage a ratchet segment 180, which is fast upon the shaft 143 to which the link 174 is secured. Although the pawl 177 is shown out of engagement with the ratchet segment, nevertheless, it normally engages said segment so as to lock the work gage and welt guide against movement away from the work.

In order that the last-mentioned parts, to wit,—the welt guide and the work gage may be moved away from the work positively, I have attached to the segment 180, a second ratchet segment 181 whose teeth project in the opposite direction. A rigid pawl 182 on the end of a loose arm 183 normally rests upon the segment 181, being held thereagainst by a spring 184. The other end of the arm 183 is pivotally connected to one arm 185 of a two armed lever, the other arm 186 of which has at its free end a roll 187 projecting into a cam groove on the left hand face of the cam disk 43. This cam groove is so formed that during each rotation of the power shaft 39, the pawl 182 engages the segment 181 and rocks the shaft 143 so as to move the bar 159 rearwardly. Both pawls 177 and 146 must be released from their respective ratchets 180 and 144, and consequently I provide the arm 183 with two oppositely projecting pins 188, 189 which engage fingers on said pawls and rock them about their pivot 178 as shown in Fig. 11. The forward movement of the arm 183 first causes the pawls 177 and 146 to release their ratchets, after which the pawl 182 engages the segment 181 to rock the shaft 143 as described.

In order to rock the shaft 143 through a longer or shorter arc, as may be desired, I provide means for preventing the engage-

ment of the pawl 182 with its segment through a part of its movement. The arm 183 normally rests upon an eccentric portion of the pin 178 and the under edge of said 5 arm is curved so that, when it moves forward, it may drop under tension of the spring 184 into engagement with the segment 181. The pin 178 may be rotated to move the eccentric portion thereof to permit 10 the engagement of the pawl 182 during the first or the latter part of its forward movement. The pawl 177 has a pin 191 similar to the pin 149 on the pawl 146 which is engaged by the finger 150 when the power 15 shaft 39 is rotated reversely to operate the lever 1128. The effect of this is to move the pawl 177 away from the ratchet 180 so as to unlock the work gage and welt guide. The lever 1128 has also another finger 190 which, 20 when the said lever is rocked, engages a pin 192 on the segment 180 so as to rock said segment through a relatively long arc to withdraw the work gage and welt guide rearward from the work to permit of the removal of the latter and the insertion of 25 another shoe to be sewed.

From this description, it will be seen that the welt guide and the work gage are positioned automatically by the work and that 30 they are always moved rearwardly the same distance each time the work is being fed. I have found that this rearward movement need not be over one-sixteenth of an inch, although the length of the movement may 35 be varied by adjusting the eccentric pin 178. The operation of the machine is substantially as follows:—

Assuming that the needle is out of the work, that the channel guide is likewise 40 away from the work, that the thread finger is at its forward extreme of movement, that the welt guide and the work gage are pressed forward against the work and locked, and that the take-up is down or at its lower 45 extreme of movement, the complete rotation of the power shaft causes the parts to be operated in the following sequence.

It should be first stated that the needle, after having fed the work and after having 50 drawn the loop through the work, moves forward slightly as it returns to its initial feeding position, so as not to strain the loop, and the needle guard also begins its forward movement. The needle is caused to 55 penetrate the work, the rearward movement of the lever 60 causing the channel guide to be moved into the channel so as to engage the work. The needle-guard carrier and needle carrier are moved toward the work, 60 the needle-guard carrier moving positively and rapidly forward as previously explained. As soon as the needle enters the work, the welt guide and work gage are unlocked and the take-up lever starts to 65 take up the thread so as to set the preced-

ing stitch. The needle continues to penetrate the work and the take-up to set the stitch, and the welt guide and work gage are moved rearwardly, during which rearward movement, the needle starts to feed 70 the shoe, the slide, which carries the needle carrier and the needle-guard carrier, moving to the left for this purpose. As the needle feeds the work and approaches its final stopping point, the looper commences to 75 lay the loop of thread about the needle, the thread finger moving rearwardly so as to draw off the sufficient amount of thread for the next stitch and the take-up moving upwardly so as to give up the thread. The 80 looper, as previously stated, moves through an arc of substantially 450° so as to cross the bights of the loop on the needle. As soon as the needle has completed its lateral feeding movement, the cam 43 operates the 85 lever 186 to release the segment 181 and permit the spring to force the work gage and welt guide forwardly so as to engage the work, the pawl 177 locking them in their 90 engaged position. During this time, the 95 needle is at the forward extreme of its movement, the looper has completed its arc of 450° , the take-up has completed its downward movement, and the welt guide and work gage are locked in their forward positions. The needle commences its rearward movement, the needle guide moving forward slightly, as the toggle straightens. As the needle draws the loop backwardly through the work and just before the hook of the 100 needle reaches the work, the thread hook or thread finger moves forward so as to release the thread. The needle continues 105 its rearward movement, and just before it reaches its limit, the looper is caused to rotate in the opposite direction through an arc of approximately 90° to bring it to its original starting point, and just as this is occurring the needle reaches its extreme 110 of rearward movement and the channel guide is moved forward away from the work. As this rearward limit of movement of the needle is being reached, and after the channel guide has been moved away 115 from the work, the needle returns to its initial starting point or position for feeding. If the operator desires then to remove the work from the machine, he rotates the power shaft reversely, and the cam projection 43, engaging the pawl 185, rocks the 120 lever 1128 so that its finger 150 disengages the pawls from the segments 180 and 146, and the finger 190 engaging the pins 191 and 149 rocks the segments or ratchets 180 and 144 so as to draw back the work gage, 125 the welt guide, and the work rest. The same movement of the lever 1128 rocks the arm 125 so as to release the tension sheave 118 and permit the operator to draw off 130 as much thread as he may desire.

A machine embodying the invention thus described, possesses numerous advantages which will be apparent to those skilled in the art, to which advantages it will be unnecessary to refer in detail. I may mention the fact that the positive mechanism for moving the needle-guard carrier is greatly superior to a spring mechanism for accomplishing the movement thereof, for the reason that in spring-actuated needle-guard carriers, the carrier frequently fails to work, particularly if the needle be sprung, whereas when the guard is actuated positively, it is always moved to proper position with reference to the work and tends to straighten the needle in case it should be sprung or twisted. I do not herein claim the looper-actuating mechanism as it is set forth and claimed in my co-pending application, Serial No. 408,034 filed December 26, 1907, now Patent No. 1,075,082, dated Oct. 7, 1913.

Having thus explained the nature of my said invention and described a way of constructing and using the same, although without attempting to set forth all of the forms in which it may be made or all of the modes of its use, I declare that what I claim is:—

1. In a welt shoe-sewing machine having its needle arranged to enter the work tangentially with relation to the bottom of the sole and from the margin toward the body of the sole, a welt guide shaped to impart an angle to the welt and arranged to hold the welt so that the needle will penetrate in said angle, and a work gage having a broad welt-engaging surface arranged to brace the inner lip of the welt against the backward pull of the needle and its thread.

2. In a shoe-sewing machine, a welt guide, a work gage at one side of the welt guide, and a curved hooked needle arranged to enter the work from the welt side between said guide and gage, said needle being movable laterally from said guide toward the gage for feeding the work, said gage having a broad surface for engaging the stitched welt above the line of the stitches on the side from which the needle enters to resist the backward pull of the needle.

3. In a welt shoe sewing machine having a curved oscillatory needle arranged to enter the work tangentially with relation to the bottom of the sole and from the margin toward the body of the sole, a welt guide and a work gage arranged to engage the welt at opposite sides of the needle, said gage having a surface arranged to engage the inner lip of the welt to brace the same against the backward pull of the needle and its thread, and a surface arranged to engage the outer lip of the welt to brace the same against the subsequent inclined pull of the needle thread.

4. In a welt shoe sewing machine having

a curved oscillatory needle arranged to enter the work tangentially with relation to the bottom of the sole and from the margin toward the body of the sole, and two welt-engaging members arranged to brace the 70 welt on opposite sides of the needle, each of said welt-engaging members having a surface arranged to brace the inner lip of the welt to brace the same against the backward pull of the needle and its thread, and each 75 having a surface arranged to brace the outer lip of the welt against the subsequent inclined pull of the needle thread.

5. In a welt shoe sewing machine having a curved oscillatory needle arranged to enter 80 the work tangentially with relation to the bottom of the sole and from the margin toward the body of the sole, a welt guide and a work gage affixed to each other and arranged to engage the welt at opposite sides 85 of the needle, said guide and gage each having a welt-engaging surface arranged to brace the inner portion of the welt and each having a surface at an angle to the first-mentioned surface to brace the outer portion of the welt.

6. In a welt shoe-sewing machine, a curved hooked needle arranged to enter the work from the welt side, a welt guide, a member for engaging the between substance on the 95 side away from the needle to resist the inward thrust of the needle, a work-gage for engaging the needle side of the upturned portion of the between substance above the line of stitches to resist the backward pull of 100 the needle, said work-gage and said inward thrust resisting member being movable from and against the work substantially parallel to the needle hole, and means for actuating said work-gage and said member.

7. In a shoe-sewing machine, a welt guide, a work gage at one side of the welt guide, a curved hooked needle arranged to enter the work from the welt side between said guide and gage, said needle being movable laterally between the guide and gage for feeding the work, said gage having a broad surface for engaging the stitched welt between the upper edge thereof and the line of the stitches to resist the backward pull of the 115 needle and thread, and a surface for engaging the welt outside the line of stitches to resist upward pull of the needle thread.

8. In a shoe-sewing machine, a curved hooked needle, a movable support, a welt 120 guide and a work gage both mounted on said support and separated to permit the needle to reciprocate laterally between them to feed the work, means for oscillating said needle, means for laterally reciprocating 125 said needle to feed the work, and means for actuating said support to move said welt guide and work gage from and against the work.

9. In a welt shoe sewing machine, welt- 130

guiding means having angularly disposed 5
welt-guiding surfaces whereby the welt is
given a substantially L-shaped cross section,
and a work gage having angularly related
surfaces arranged to engage respectively the
two lips of the welt to brace said lips against
the stress of the needle and thread, and
means for moving said gage in a direction
at an angle to such surface and intermediate
10 of the angle of said surfaces, toward and
from the welt.

10. In a welt shoe sewing machine having
a curved oscillatory needle, a welt guide,
and means arranged to move said guide
15 bodily toward and from the shoe and keep
a predetermined stitch-receiving line of the
welt in the curved path of the needle without
out causing angular movement of said guide.

11. In a welt shoe sewing machine having
20 a curved oscillatory needle, a welt guide
formed to crease the welt, and means arranged
to move said welt guide bodily toward
and from the shoe and keep the crease
25 of the welt in the curved path of the needle
without causing angular movement of said
guide.

12. In a welt shoe sewing machine having
a curved oscillatory needle, a welt guide
formed to crease the welt, and means arranged
30 to move said welt guide bodily toward
and from the shoe in an arc concentric
to that of the needle without causing angular
movement of said guide.

13. In a shoe-sewing machine, a curved oscillatory hooked needle, a welt guide, a 35
holder for said welt guide, and oscillatory parallel links supporting said holder, the radius of said links being the same as the radius of said needle, said links being arranged to cause a portion of the welt to 40 describe an arc concentric to the axis of the needle.

14. In a shoe-sewing machine, a power shaft, stitch-forming mechanism, a work gage, a movable support therefor, a lock for 45
said support, and means for releasing said lock, comprising a ratchet on said power shaft, and a lever having a pawl arranged to be inoperative when said ratchet is rotated forwardly, and to be operated by said 50 ratchet on a reverse rotation thereof.

15. In a shoe-sewing machine, a power shaft, stitch-forming mechanism, a welt guide, a movable support therefor, a lock for 55
said support, and means for releasing said lock, comprising a ratchet on said power shaft, and a lever having a pawl arranged to be inoperative when said ratchet is rotated forwardly, and to be operated by said 60 ratchet on a reverse rotation thereof.

In testimony whereof I have affixed my
signature, in presence of two witnesses.

HARRIE A. BALLARD.
